HAIR DRYER

Otto Hubner, 199 Mauerkircherstrasse,
8000 Munich 81, Germany

Filed June 11, 1973, Ser. No. 369,054

Term of patent 14 years

Int. Cl. D28—03

U.S. Cl. D86—10 F

FIG. 1

FIG. 6

FIG. 2

FIG. 3

FIG. 5

FIG. 1 is a right front perspective view of a hair dryer embodying my new design;

FIG. 2 is a left side elevational view thereof;

FIG. 3 is a top plan view thereof;

FIG. 4 is a rear elevational view thereof;

FIG. 5 is a horizontal sectional view thereof looking along the plane of line 5—5 in FIG. 6; and

FIG. 6 is a vertical sectional view thereof looking along the plane of line 6—6 in FIG. 3.

I claim:

The ornamental design for a hair dryer, as shown.
